UNITED STATES PATENT OFFICE.

THOMAS PAIN CHAPMAN AND ANDREW LEE WHITLEY, OF ST. LOUIS,
MISSOURI; SAID WHITLEY ASSIGNOR TO SAID CHAPMAN.

ROLL-PAPER HOLDER AND CUTTER.

SPECIFICATION forming part of Letters Patent No. 369,692, dated September 13, 1887.

Application filed April 9, 1887. Serial No. 234,308. (No model.)

To all whom it may concern:

Be it known that we, THOMAS PAIN CHAPMAN and ANDREW LEE WHITLEY, citizens of the United States, residing in the city of St. Louis and State of Missouri, have invented a Roll-Paper Holder and Cutter, of which the following is a specification.

Our invention relates to improvements in paper holders and cutters in which a stationary knife is used.

The objects of our improvements are, first, economy, convenience, and neatness in handling and using wrapping-paper; second, to afford facilities for the proper adjustment of the knife by the use of a rest-block and thumb-screw; and, third, to provide a proper tension-spring to hold the paper in place independently of the knife. We attain these objects by the mechanism illustrated in the accompanying drawings, in which—

Figure I is a complete drawing of the entire holder and cutter, representing each part, with the paper partly torn and broken away, showing the knife in open position; and Fig. II, a vertical section of Fig. I, showing knife closed and tension-spring in operation.

The figures in each drawing refer to the various parts.

1 shows the paper coming from the roll and passing under the knife 5 and over the roller-bar 17.

2 is the roll of paper on the holder and cutter in proper position for use.

3 are the upright pieces of the frame of the holder and cutter, to be made of metal or other suitable material.

4 is the rest-block for the knife, attached to the upright pieces 3 3, just described.

5 is the swinging knife in open position, used for cutting the paper, and to be made of metal.

6 is the thumb-screw, which, together with the rest-block 4, holds the knife to the frame and in place.

7 is the tension-spring, bearing direct on the paper to prevent it from rolling too freely and to hold it in place while cutting with the knife on the opposite side of the holder. This spring is made of one continuous piece of wire attached to the top pieces of the frame 11 at

points 7 7, (indicated in Fig. I,) where the wire is coiled for the purpose of securing the proper tension. The wires extend downward to the center of the roll of paper 1 and bear direct on it.

8 is the open slot in the knife to allow it to slip under the head of the thumb-screw without removing the screw from the block 4.

9 is the base of the holder and cutter, to be made of wood or other suitable material.

10 is the thumb-piece of the knife, for holding between thumb and finger when opening to place paper in position.

11 is the top piece of the frame, to be made of wood or other suitable material.

12 12 are the screws for fastening the frame together.

13 is the socket for the shaft to revolve in.

14 is the shaft set in the ends of the wood roller, and to be made of metal, of any suitable size.

15 is the wood roller, made of wood, of any suitable size, and used for carrying the paper. This roller passes from one upright piece to the other, 3 3, through the center of the paper 1, and rests at each end in the sockets 13.

16 shows the opening of the socket to let the shaft of the roller drop into position.

17 is the roller-bar for holding the paper against the knife so that it can be cut. It also holds the paper from the roll so that it can be caught with the thumb and finger without having to turn roll of paper. When the holder and cutter are in use, the paper passes between the roller-bar and the swinging knife 5. This bar is to be made of metal or any other suitable material.

We are aware that prior to our invention roll-paper holders and cutters have been in use made with a knife and a spring combined.

We do not claim such a combination, broadly, or such a combination at all; but

What we do claim as our invention, and desire to secure by Letters Patent, is—

1. In a roll-paper holder and cutter, the combination of a swinging knife, 5, adjusted and held in position by means of a rest-block, 4, upon which the knife rests when in place, and a thumb-screw, 6, and a tension-spring bearing direct upon the roll of paper to hold

it in place while the paper is being cut, as above described.

2. The combination, in a roll-paper holder and cutter, of a swinging knife, 5, operated independently of the tension-spring 7, the knife being adjusted by means of the rest-block 4 and thumb-screw 6, as above set forth, and a roller-bar, 17, to hold the paper against the knife while it is being cut and after cutting to hold the paper from the roll, so that it can be easily caught when it is desired for use.

3. The combination, in a roll-paper holder and cutter, of a tension-spring, 7, bearing direct upon the paper to hold it firmly while the knife is cutting, and a roller-bar, 17, to hold the paper against the knife while the latter is at work, and also to hold the paper in proper position at all times.

4. In a roll-paper holder and cutter, a swinging knife, 5, operated independently of the tension-spring 7, the knife being adjusted and held in position by means of a rest-block, 4, upon which it rests, and a thumb-screw, 6, substantially as set forth.

5. In a roll-paper holder and cutter, the following combination: a swinging knife operated independently of the tension-spring, a tension-spring bearing direct upon the paper

to hold it in place and firmly while it is being cut, a rest-block affording proper facilities 30 for the adjustment of the swinging knife, as above described, and a roller-bar to hold the paper against the knife when the latter is at work and to hold the paper from the roll, so that the paper can be easily caught when it is desired 35 for use.

6. The combination, in a roll-paper holder and cutter, of a roller-bar, 17, to hold the paper in place while it is being cut and also from the roll, so that it may be conveniently caught 40 between the thumb and finger when it is desired for use, a tension-spring, 7, bearing direct upon the roll of paper, and a swinging knife adjusted and held in position by means of the thumb screw 6 and rest-block 4, substantially as above described.
